UNITED STATES PATENT OFFICE

LOUIS L. RUSTAD, OF MINNEAPOLIS, MINNESOTA

DESIGN FOR A COMPOSITE CHARACTER SIGN

Application filed April 29, 1931. Serial No. 39,651. Term of patent 14 years.

To all whom it may concern:

Be it known that I, LOUIS L. RUSTAD, a citizen of the United States, residing at Minneapolis, in the county of Hennepin and State of Minnesota, have invented a new, original, and ornamental Design for Composite Character Signs, of which the following is a specification, reference being had to the accompanying drawings, forming part thereof.

Fig. 1 is a front elevational view of a composite character sign showing my new design; and

Fig. 2 is a perspective view of said composite character sign.

I claim:

The ornamental design for a composite character sign as shown.

LOUIS L. RUSTAD.
